P. B. KROUT

WIRE CLAMP

Filed Nov. 2, 1925

FIG. I.

FIG. II.

FIG. III.

INVENTOR:

PALLED BERTRAM KROUT,

*By Arthur E. Baugh,
Attorney.*

UNITED STATES PATENT OFFICE.

PALLED BERTRAM KROUT, OF NARBERTH, PENNSYLVANIA.

WIRE CLAMP.

Application filed November 2, 1925. Serial No. 66,288.

To all whom it may concern:

Be it known that I, PALLED BERTRAM KROUT, a citizen of the United States, residing at Narberth, in the county of Montgomery and State of Pennsylvania, have invented a certain new and useful Improvement in Wire Clamps, whereof the following is a specification, reference being had to the accompanying drawings.

10. My invention relates to devices adapted for clamping stranded cables formed of a plurality of spirally laid wires. Ordinarily, such clamps do not include any means for determining the rotary position of the cable with reference to the clamping means. However, with reference to the direction of pressure of the clamp upon the cable is of paramount importance in attaining the maximum holding effect of the clamp; because such cables are not truly circular but polygonal in cross section and, consequently, are regularly of different diameters, in different radial directions, and throughout their length. Therefore, my improvement 20 includes means designed and adapted to insure that such a cable shall be guided to, and held in, the most efficient relation to the clamp, which is with a minimum diameter of the cable presented and maintained between the oppositely compressed members of 25 the clamp.

As hereinafter described, the specific features of my invention above contemplated are exemplified with reference to a cable 30 formed of seven wires, of which one is axial and the other six disposed in symmetrical relation encircling the axial wire. However, such a cable may be employed as the core of a nineteen wire cable by laying twelve additional wires spirally around such a seven wire cable.

40. My invention includes the various novel features of construction and arrangement hereinafter more definitely specified.

45. In said drawings; Fig. I is a plan view of a simple form of my invention, wherein two cables may be simultaneously clamped in parallel relation.

50. Fig. II is a longitudinal sectional view taken on the line II, II in Fig. I.

Fig. III is a transverse sectional view taken on the line III, III in Figs. I and II.

55. In said figures; two clamp blocks 1 and 2, conveniently formed of the same outer configuration, are opposed and clamped together by three bolts 4 provided with nuts 5.

Said bolts extend through registered openings 6 and 7 in the respective clamps 1 and 2, which openings are preferably similarly squared as indicated in Fig. I so as to prevent rotation of said bolts by engagement with the squared shanks 9 of the latter; the arrangement being such that it is immaterial which way the bolts are placed in the clamp. That is to say, although all of said bolts are indicated with their heads exterior to the clamp block 1, they may be placed with their heads exterior to the clamp block 2; but it is more convenient to dispose the central bolt in the opposite direction to the end bolts, as indicated in dotted lines in Fig. II, to afford more convenient access to the nut 5 thereon.

60. Said clamp block 1 is provided with two parallel grooves 11 with spirally extending flutes 12 therein adapted to respectively fit and engage the wires of the two similar cables 14 and 15. Said flutes are so disposed as to insure that minimum diameters of each of said cables 14 and 15 shall be presented in the transverse planes coinciding with the crests of the respective cam surfaces 17 which are formed in each of the grooves 18 in said clamp block 2 and preferably coinciding with transverse planes intersecting the axes of said bolts 4.

65. Referring to Fig. III; it may be observed that the construction and arrangement above described are such that when said clamp blocks 1 and 2 are compressed toward each other, by rotation of said nuts 5 upon said bolts 4; the effect is to grip said cables 14 and 15 at their regions of minimum diameter and with the effect of spreading into more intimate gripping contact with the sides of 70 said grooves 11, the wires which are at the outer radii of said cables in the horizontal diameter thereof shown in Fig. III.

75. Although only short pieces of said cables 14 and 15 are shown in said figures; it is to be understood that said clamp may be used either to connect two entirely distinct and separate cables or one of said pieces 14 and 15 may be the end of a bight of the other.

80. However, the clamping action above described is the same in either case. Moreover, although I have shown a clamp which is adapted to thus secure in parallel relation two portions of cable of the same diameter; it is to be understood that the grooves 11 and 18 may be of different sizes so that cables of different diameters may be con- 85

nected by a single clamp block. Furthermore, although I have shown said grooves 11 and 18 of the same diameter throughout the length of the respective blocks 1 and 2; it is to be understood that they may be larger at one end than at the other, for instance, to engage at the larger end a nineteen wire cable, by clamping the outer congeries thereof; the seven wire core of such a cable being secured in the smaller groove at the other end of the clamp, as shown in the drawings.

Therefore, I do not desire to limit myself to the precise details of construction and arrangement herein set forth, as it is obvious that various modifications may be made therein without departing from the essential features of my invention as defined in the appended claims.

I claim:

20 1. In a wire cable clamp; the combination with a metal block having a groove extending longitudinally therein, corresponding with the exterior diameter of a cable; said groove having flutes in the bottom thereof corresponding in spiral curvature with the pitch and lay of the wires in a cable; said block having a bolt hole extending therethrough; of a second metal block having a bolt hole extending therethrough in registry with said bolt hole in the first metal block, and having a groove extending longitudinally therein, corresponding with the exterior diameter of a cable, and adapted to register with the groove in said first block 25 and having projections in said second metal block arranged to respectively register with regions of minimum diameter of a cable positioned in said clamp by said flutes; and a bolt arranged to extend through said registered bolt holes and having a nut; whereby said blocks may be compressed toward each other to clamp a cable at regions of minimum diameter.

25 2. In a clamp for stranded wire cables having different diametrical dimensions; the combination with a metal block having two cable seats therein, each including a groove extending from end to end of said block and having flutes therein corresponding in spiral curvature with the pitch and lay of the wires in the cable; of a second metal block having two cable seats therein, comprising respective longitudinal grooves adapted to register 30 with the grooves in said first block and having cam surfaces with respective crests presented at regions of minimum diameter of said cables; each of said blocks having square openings therethrough in registered relation; bolts having heads with squared shanks adapted to fit in said openings and extend through both of said blocks; and nuts for said bolts, whereby said blocks may be compressed toward each other and grip cables 35 in said grooves.

30 through in registered relation; bolts having heads with squared shanks adjoining the heads, adapted to fit in said openings and extend through both of said blocks; and nuts for said bolts, whereby said blocks may be compressed toward each other and grip cables in said grooves. 60

3. In a wire cable clamp; the combination with a metal block having two parallel grooves extending longitudinally therein, and each corresponding with the exterior diameter of a cable; said grooves having flutes in the bottom thereof corresponding in spiral curvature with the pitch and lay of the wires in a cable; said block having a series of bolt holes extending therethrough; of a second metal block having bolt holes 75 extending therethrough in registry with the bolt holes in the first metal block, and having two grooves extending longitudinally therein, each corresponding with the exterior diameter of a cable, and adapted to register with the grooves in said first block and having projections in said second metal block arranged to respectively register with regions of minimum diameter of two cables positioned in said clamp by said flutes; and bolts arranged to extend through said registered bolt holes and having nuts; whereby said blocks may be compressed toward each other to clamp two cables at regions of minimum diameter. 80

4. In a clamp for stranded wire cables having different diametrical dimensions; the combination with a metal block having two cable seats therein, each including a groove extending from end to end of said block and having flutes therein corresponding in spiral curvature with the pitch and lay of the wires in a cable; of a second metal block having two cable seats therein, comprising respective longitudinal grooves adapted to register 95 with the grooves in said first block and having cam surfaces with respective crests presented at regions of minimum diameter of said cables; each of said blocks having square openings therethrough in registered relation; bolts having heads with squared shanks adapted to fit in said openings and extend through both of said blocks; and nuts for said bolts, whereby said blocks may be compressed toward each other and grip cables 100 in said grooves. 105

In testimony whereof, I have hereunto signed my name at Philadelphia, Pennsylvania, this 31st day of October, 1925.

PALLED BERTRAM KROUT.
